UNITED STATES PATENT OFFICE.

ROBERT FISCHER, OF BROOKLYN, NEW YORK, ASSIGNOR TO MAX H. FISCHER, OF NEW YORK, N. Y.

SCARF-PIN HOLDER.

13,740.

Specification of Reissued Letters Patent. Reissued May 26, 1914.

Original No. 963,537, dated July 5, 1910, Serial No. 532,473. Application for reissue filed October 30, 1912. Serial No. 728,747.

To all whom it may concern:

Be it known that I, ROBERT FISCHER, a citizen of the United States, residing at Brooklyn, in the county of Kings and State 5 of New York, have invented new and useful Improvements in Scarf-Pin Holders, of which the following is a specification.

This invention relates to scarf pin holders and its object is to provide an obstruction to 10 be secured to the end of the scarf pin to prevent its removal after once being placed in position on the scarf, but which can be readily removed when desired, as will be more fully explained in the following specification, set forth in the claims and illustrated 15 in the drawings, wherein:

Figure 1 is an elevation of the holder; Fig. 2 is a sectional view of same; Fig. 3 shows a similar view with the pin released; 20 Fig. 4 is a detail view of the clutch mechanism; Fig. 5 is a washer filling the lower end of the holder; Fig. 6 is the clutch; and Fig. 7 is a modified form.

The holder consists of a thimble 10 preferably stamped of sheet metal and having its upper end 11 closed and in which is a perforation 12 for the passage of the pin 13. The lower end of the thimble is closed by means 25 of the washer 14 having the perforation 15 30 and the slot 16.

Within the thimble is carried a slide frame 17 having at its upper end a perforation 18 and ears 19 and in the latter is journaled a clutch 20 having a perforation 21 35 with sharp edges which are adapted to engage and hold the pin 13 when set at an angle as shown in Fig. 2, but when the clutch is turned to a horizontal position as shown in Fig. 3, the pin 13 is free to pass 40 through same.

Beneath frame 17 and between it and the washer 14 is a spring 22 which forces the frame 17 and the clutch 20 upward causing the latter to come in contact with the projection 23 struck in one side of the thimble 10 and which throws the clutch 20 at an angle to cause the edges of the perforation 21 to bite and retain the pin.

When it is desired to loosen the pin by 50 changing the position of the clutch 20, the frame 17 is pulled downward by means of a tail 24 which extends through the slot 16 and whose lower end is provided with a per-

foration 25 through which the pin is adapted to pass.

The drawings show the invention on a greatly enlarged scale and in practice the tail 24 is operated by the finger nail of the user but may be found desirable to employ a ball 26 such as shown in Fig. 7 by which 60 the frame 17 may be manipulated.

The device is simple and efficient in operation and its parts may be stamped from sheet metal and assembled at a small cost. It may be used to secure scarf pins, hat pins 65 and other similar articles by simply passing the pin through the various perforations shown in the drawings and the spring 22 renders the device automatic as it operates the slide to throw the clutch in the position 70 to grasp the pin.

It is obvious that the parts may be otherwise arranged or modified without departing from the essential features above described.

What I claim as new and desire to secure by Letters Patent is:

1. In a pin holder, the combination with a thimble having a projection, of a movable frame therein, a perforated clutch carried 80 by the frame and adapted to be operated by the projection, and a spring adapted to cause the clutch to come in contact with the projection.

2. In a pin holder, the combination with a 85 thimble having perforated ends, and a projection within such thimble; of a frame sliding in the thimble, a spring interposed between the frame and the bottom of the thimble, and a pivoted perforated plate carried 90 by the frame and adapted to assume its operative position when in contact with the projection.

3. In a pin holder, the combination with a member provided with a pin receiving aperture, of another member slidable longitudinally relative thereto, a clutch plate pivotally mounted on one of such members, means associated with the other member for engaging and actuating such clutch plate into 100 operative position, a spring for normally forcing the clutch plate and engaging means into contact, and means for permitting the relative movement by user of such clutch plate and engaging means against the action 105 of the spring to release the pin.

4. In a pin holder, the combination with a member provided with a pin receiving aperture, another member slideable longitudinally within the same, a clutch plate pivotally mounted on the inner member and having a centrally located perforation, means on the outer member for engaging and tilting such clutch plate into pin gripping position, a spring normally forcing the perforated clutch plate and tilting means into contact and means for permitting the relative movement by the user of the aforesaid members against the action of said spring to release the pin.
- 15 5. The combination, in a scarf pin holder, of a thimble adapted to receive the end of the scarf pin, a releasing member slideable longitudinally relative to said thimble, a

tiltable clutch plate within the thimble, having a part associated with said releasing member and provided with a perforation to receive the pin, a projection extending within the thimble for tilting said clutch plate to grip the pin, a spring for normally forcing the clutch plate toward said tilting projection,—the releasing member and thimble being so relatively disposed and arranged as to permit the application of pressure therebetween by the fingers of the user to cause the clutch plate to assume its non-gripping position.

ROBERT FISCHER.
